United States Patent Office

Des. 186,307
Patented Oct. 13, 1959

186,307

UPRIGHT CHAIR OR SIMILAR ARTICLE

Vladimir Kagan, New York, N.Y.

Application February 10, 1959, Serial No. 54,539

Term of patent 3½ years

(Cl. D15—1)

FIG. 1.

FIG. 2.

Fig. 1 is a rear perspective view of an upright chair embodying my new design; and

Fig. 2 is a front perspective view thereof.

I claim:

The ornamental design for an upright chair or similar article, substantially as shown.
